SUPERREGENERATIVE RECEIVER

Johan Machiel Schmidt and Johannes Jacobus Zaalberg van Zelst, Eindhoven, Netherlands, assignors to Hartford National Bank and Trust Company, Hartford, Conn., as trustee

Application July 30, 1951, Serial No. 239,262

Claims priority, application Netherlands August 23, 1950

3 Claims. (Cl. 250—20)

1

The invention relates to superregenerative receivers. Such receivers are known to have a discharge tube operating as an oscillator, whose frequency is determined by the input signal circuit, and whose damping is varied by a so-called quenching oscillation in a manner such that for a portion of the quenching oscillation period, the amplitude of the oscillations across the circuit will increase from a definite low initial value varying with the strength of the signal to be received to a definite final value and rapidly drop again to the initial value for the remaining portion of this period. The operation is based on the fact that the final value of the high-frequency voltage across the circuit varies with the value of the initial voltage. The beginning of the time during which the voltage increases is the moment at which the circuit-arrangement is sensitive. This may be termed the sensitivity moment. Apart from the noise voltage only a signal voltage is to prevail at this moment across the circuit.

As usual, the tube may comprise a cathode, an anode and a control-grid; a circuit tuned to the incoming frequency, and responsive to an incoming signal is connected between the cathode and the control-grid, the anode circuit being coupled with the grid circuit in a manner such that positive feed-back occurs, so that a negative damping effect is produced across the circuit, and the amplitude of the oscillations across this circuit is increased. It is also common practice to interrupt, or strongly reduce, periodically the anode current through the action of the quenching oscillation, so that for the quenching period the oscillation amplitude decreases owing to the natural damping of the circuit. It is known to introduce herein an additional damping, for example, with the use of a second tube which is negatively coupled back.

It has furthermore been suggested to use oscillator tubes operating on the dynatron principle, or magnetrons in superregenerative receivers.

In order to ensure a satisfactory amplification in superregenerative receivers, the amplitude of the oscillation is to increase by approximately a factor 10^6 and decrease again in a single cycle of the quenching oscillation, which is composed of a negative damping period and a positive damping period. The quenching period is to be so long that at the end of the positive damping period the oscillations may have dropped below the noise level. The required amount of positive or negative circuit damping must be sufficient to increase or

2

decrease the oscillation amplitude within a sufficiently short time. On the other hand, in all devices of this kind, the frequency of the quenching oscillation must be high relative to the highest modulation frequency of the oscillations to be received. It may be inferred therefrom that the band width of the circuit is to be approximately ten times the maximum modulation frequency.

10 In the known circuit-arrangements the decrease in damping of the input oscillation circuit at the beginning of that part of the quenching period in which the amplitude of the oscillations increases is generally accompanied with a comparatively large variation of the anode current of the tube, thus causing the negative damping. It has been found that this variation of the anode current causes an interfering switching-on phenomenon. The abrupt variation of the anode current produces a voltage pulse across the input oscillation circuit, so that oscillations are produced which will interfere with proper circuit operation if their amplitude corresponds with the signal amplitude across the circuit at the beginning of the negative damping period. 25 This effect inter alia prevents longer waves from being received with adequate sensitivity.

In other circuit-arrangements, in which the damping is not produced through the cut-off or the reduction of the anode current, current variations are produced which give rise to similar effects. The amplitude of all these interfering oscillations will increase with increasing quenching frequency, and the impedance of the circuit will be increased accordingly. Consequently, superregenerative radio reception with longer waves of, for example, over 100 m., is no longer possible, as due to the increased circuit impedance the usual quenching interruption frequency of, for example, 30,000 C./S. will produce strong interference pulses.

30 The object of the invention is to provide a receiver of the kind described in the preamble, in which the said switching-on phenomenon is reduced to have a negligible effect. Therefore, this new receiver will be adapted to the reception of oscillations of longer wavelength, for example, of more than 100 m. Since, for the same reason, it is possible to choose a considerably higher 35 quenching frequency in the inventor's circuit-arrangement than in the known circuit-arrangements, the new receiver is at the same time suitable for the reception of high-frequency oscillations, which are modulated in a very wide frequency range, such as used in television.

The invention consists in producing the required damping of the input oscillation circuit for the period in which the amplitude of the oscillation decreases through the use of a parallel connection of resistors coupled to the circuit instead of using variation of the anode current of the tube or of other direct currents. With the use of means to be described in detail hereinafter this positive damping is again obviated at the beginning of the oscillation period without producing an appreciable voltage pulse across the input oscillation circuit. It is thus ensured that no switching-on phenomenon occurs at the sensitivity moment.

In this case one or more rectifiers which are periodically brought into a non-rectifying state under the action of the interruption frequency are preferably connected in parallel with the circuit.

It should be noted here that it is known to increase the damping of the input oscillation circuit in superregenerative receivers during the time in which the oscillation is to be reduced, with the use of a rectifier connected in parallel with circuit; however, it has not been recognized that an abrupt variation of current may produce interfering phenomena, while at the same time a variation of the anode current or of a direct current passing through the rectifier occurs. In super-regenerative receivers comprising a magnetron as the oscillator it has furthermore been suggested to produce the damping by means of a discharge tube comprising a control-grid across which the quenching frequency is operative. In this case, a variation of the direct current passing through the latter tube occurs at the beginning of the oscillation period.

In a superregenerative receiver it is furthermore known to connect two tubes in the input oscillation circuit in push-pull so that the anode circuits act in parallel on the load. In this case, however, one tube exclusively serves for producing damping for the other. Since the quenching oscillation is supplied in phase opposition to the tubes, the total direct current component of the anode current may be regulated to vary only slightly. However, in this manner it is not possible to eliminate the aforesaid switching-on phenomenon as this would require an adjustment of the currents so accurate as to be unobtainable in practice.

In order that the invention may be more clearly understood and readily carried into effect, it will now be described more fully with reference to the accompanying drawing, in which Fig. 1 and 2 show alternative embodiments of the invention and in which Figs. 3, 4 and 5 are graphs which aid in the explanation of the invention.

Fig. 1 shows a circuit-arrangement comprising a single tube operating as a superregenerative detector, shown here as a triode for the sake of simplicity. The oscillations coming from the aerial are inductively supplied to the input oscillation circuit comprising an inductance 2 and a variable capacitor 3. This circuit is grounded at one end and connected at the other end through a capacitor 4 to the control-grid of a tube 5. The anode of the latter is connected through a feedback coil 7 coupled with the inductance 2 and through a resistor 8 to the positive terminal 9 of the current supply. The modulation oscillations are taken from terminals 9. The grid of the tube is grounded through a leak resistor 6.

The feedback is such that it produces across the circuit 7 spontaneous oscillations which are

periodically quenched in accordance with the superregenerative principle. According to the invention, this is effected in the circuit-arrangement shown by connecting in parallel with the circuit the series combination of a resistor 11 and a rectifier 12. To the terminals 10 of the resistor 11 is connected a quenching frequency generator. The characteristic curve of the latter is approximately a rectangular wave.

As is indicated in Fig. 3 by the broken line, the leading edges of the voltage waves are slightly rounded off; the horizontal line of Fig. 3 indicates the zero line at which no bias voltage is operative across the rectifier 12. The rectifier 12 operates as a virtual rectifier, which only rectifies the positive halves of each cycle of the high-frequency voltage operative across circuit 2, 3. At the time of such rectification the circuit is damped to such an extent that the oscillations produced across it by the oscillator tube rapidly decrease in amplitude to a very low value. If during the occurrence of a positive voltage pulse the upper terminal 10 becomes positive, the rectifying action abruptly ceases, which, however, is not attended by a variation of the direct current component across the circuit. The damping of the circuit 2, 3 due to the rectifier action is eliminated so that the oscillations across this circuit can increase. At the end of the positive voltage pulse the voltage at the upper terminal 10 becomes again equal to that of the lower terminal, and the oscillations produced by the oscillator tube again vanish rapidly. The gradual increase of the positive voltage at the upper terminal is intended to avoid a current pulse across the capacitance of the rectifier. The reduction of the voltage at the upper terminal to zero may be comparatively abrupt without adversely affecting the circuit, since, at the instant when the damping occurs, the oscillations across the circuit have so large an amplitude, with respect to whatever oscillations which may be produced by current pulses due to this reduction that the circuit is relatively unaffected.

The wave form of the quenching interruption oscillation need not be rectangular; as an alternative, this voltage may be composed of a sine voltage superposed on a direct voltage, which is approximately equal to the maximum value of the sine voltage, as is shown in Fig. 4. As a further alternative, use may be made of a saw-tooth voltage preferably having a steep trailing edge (Fig. 5). However, in all cases the voltage should be such that the rectifier cannot carry an appreciable direct current component.

The rectifier 12 should preferably have a sharply bentover characteristic curve, so that it will have a low internal resistance at a low amplitude of the high-frequency oscillations in the circuit. The maximum value of the resistor 11 is set by the requirement that the parallel combination 11, 12 should exert a strong damping influence on the circuit 2, 3. This requirement also determines the resistance of the rectifier 12 in rectifying condition.

If the rectifier 12 has excessive capacitance when a positive voltage pulse is produced at the upper terminal of the resistor 11, the resultant charge current may cause a switching-on phenomenon which produces interfering oscillations. Consequently, this capacitance should be low, for example lower than 1 micro-microfarad. It has been found that for the purpose of the invention, so-called crystal rectifiers are particularly suit-

able, although normal diodes may also yield satisfactory results. Germanium rectifiers are very suitable, since they have not only a low capacitance but can also resist comparatively high voltages, for example, 50 v. and upwards. This is of importance since the cut-off voltage of the rectifier is to be higher than the maximum amplitude of the high-frequency oscillation in the circuit. The latter voltage may, for example, be of the order of 10 v.

Since the anode current of the tube remains constant and other variations of the direct current do not occur in the circuits when a positive voltage pulse occurs, the aforesaid switching-on phenomenon does not occur. It has been found that thus the waves in the range from 200 to 600 meters can be received with satisfactory results.

Fig. 2 shows a circuit-arrangement, in which use is made of a push-pull combination of two discharge tubes 15 and 16. In this case the oscillation circuit is connected between the anodes of the tubes; the circuit inductance 14 is provided with a central tap. The anode circuit furthermore comprises the resistor 8, from the lower end of which the modulation voltage is taken at the terminals 9.

Because of the connection of the anode of tube 15 through a capacitor 18 to the grid of tube 16, and the connection of the anode of tube 16 through a capacitor 17 to the grid of tube 15, oscillations are produced in tubes 15 and 16. Leak resistors 19 and 20 are provided between the grids and the interconnected cathodes.

Furthermore, two rectifiers 21 and 22, preferably germanium rectifiers, are connected, in opposite sense, in parallel with the circuit 3, 14. The junction of these rectifiers is connected through a resistor 11 to the central tap on the coil 14. The quenching oscillation is supplied through terminals to resistor 11. This quenching oscillation has such a wave form that a direct current component cannot pass through the rectifier.

The operation of the circuit-arrangement shown in Fig. 2 is otherwise identical with that of the circuit-arrangement shown in Fig. 1.

The rectifiers may be replaced by other elements, for example, controlled discharge tubes, by means of which the circuit is short-circuited or strongly damped during the damping period. The short-circuit may even be carried out with the use of a mechanical switch. This may be of importance for measuring purposes, if the frequencies are very low. However, care should be taken that no strong direct-current variations occur at the beginning of the negative damping period.

What we claim is:

1. In a superregenerative receiver wherein an incoming signal is regenerated and periodically quenched by a quenching oscillation, the combination comprising a pair of electron discharge tubes each having a cathode, a control grid and an anode, a push-pull resonant circuit tuned to said incoming signal and including a center-tapped inductor connected between the anodes of

said tubes, means to cross-couple the grids and anodes of said tubes to effect regeneration, means to apply an operating potential for said tubes between the cathodes thereof and the center-tap of said inductor, a pair of unidirectionally conductive devices, a damping resistance for said resonant circuit having one end connected to said center-tap and having the other end connected in one direction through one of said devices to the anode of one tube and connected in the other direction through the other of said devices to the anode of the other tube, and means to apply the quenching oscillation across said damping resistance.

15 2. In a superregenerative receiver wherein an incoming signal is regenerated and periodically quenched by a quenching oscillation, the device comprising a pair of electron discharge tubes each having a cathode, a control grid and an anode, a push-pull resonant circuit tuned to said incoming signal and including a center-tapped inductor connected between the anodes of said tubes, means to cross-couple the grids and anodes of said tubes to effect regeneration, means to apply an operating potential for said tubes between the cathodes thereof and the center-tap of said inductor, a pair of rectifiers, a damping resistance for said resonant circuit having one end connected to said center-tap and having the other end connected in one sense through one of said rectifiers to the anode of one tube and connected in the other sense through the other of said rectifiers to the anode of the other tube, and means to apply the quenching oscillation across said damping resistance.

30 3. In a superregenerative receiver wherein an incoming signal is regenerated and periodically quenched by a quenching oscillation, the device comprising a pair of electron discharge tubes each having a cathode, a control grid and an anode, a push-pull resonant circuit tuned to said incoming signal and including a center-tapped inductor connected between the anodes of said tubes and a variable condenser connected across said inductor, capacitive means to cross-couple the grids and anodes of said tubes to effect regeneration, means to apply an operating potential for said tubes between the cathodes thereof and the center-tap of said inductor, a pair of germanium diodes, a damping resistance for said resonant circuit having one end connected to said center-tap and having the other end connected in one sense through one of said diodes to the anode of one tube and connected in the other sense through the other of said diodes to the anode of the other tube, means to apply the quenching oscillation across said damping resistance, and means coupled between said center-tap and said cathodes to obtain an output voltage.
